UNITED STATES PATENT OFFICE.

OTTO FORTHMILLER, OF MINNEAPOLIS, MINNESOTA, ASSIGNOR OF ONE HALF TO JOHN J. MAIER, ONE-SIXTH TO GUSTAVE FORTHMILLER, AND ONE-SIXTH TO KARL FORTHMILLER, ALL OF MINNEAPOLIS, MINNESOTA.

LOCK-ACTUATED CIRCUIT-BREAKER FOR IGNITION SYSTEMS OF EXPLOSIVE-ENGINES.

1,298,322.

Specification of Letters Patent. Patented Mar. 25, 1919.

Application filed April 5, 1918. Serial No. 226,328.

To all whom it may concern:

Be it known that I, OTTO FORTHMILLER, a citizen of the United States, born in Germany in 1896, came to the United States in 5 1913, took out first papers in September, 1917, residing at Minneapolis, in the county of Hennepin and State of Minnesota, have invented certain new and useful Improvements 10 in Lock-Actuated Circuit-Breakers for Ignition Systems of Explosive-Engines; and I do hereby declare the following to be a full, clear, and exact description of the invention, such as will enable others skilled in the art to which it appertains to make and use the 15 same.

My invention has for its object to provide an extremely simple and highly efficient lock actuated circuit breaker for ignition systems of explosive engines; and to this 20 end, generally stated, it consists of the novel devices and combinations of devices herein-after described and defined in the claims.

In the accompanying drawings, which illustrate the invention, like characters indicate like parts throughout the several 25 views.

Referring to the drawings:

Figure 1 is a fragmentary front elevation of an automobile dash having the invention 30 applied thereto, some parts being shown in different positions by means of broken lines;

Fig. 2 is a transverse section, taken on the line 2-2 of Fig. 1;

Fig. 3 is a horizontal section, taken on the 35 line 3-3 of Fig. 2;

Fig. 4 is a vertical section, taken on the line 4-4 of Fig. 2, on an enlarged scale; and

Fig. 5 is a vertical section, taken on the 40 line 5-5 of Fig. 2, on an enlarged scale.

The numerals 6 and 7 indicate, respectively, the dash and hood of an automobile, and the numeral 8 indicates the wires of the ignition system leading from the magneto, battery, or other source of electrical energy, 45 to the spark plugs of an internal combustion engine.

Interposed in the wires 8 of the ignition system is my improved lock actuated circuit breaker, which includes a plurality of fixed contacts 9 and a plurality of co-operating

movable contacts 10, mounted in a metal housing 11, secured to the back of the dash 6 by screw bolts 12, passed through said dash from the front thereof. All of the fixed contacts 9 are mounted on a horizontal 55 fixed bar 13, and all of the movable contacts 10 are mounted on and carried by a horizontal movable bar 14, located, the latter below the former. Both of these bars are made from fiber or other suitable insulating 60 material, and the number of pairs of contacts 9 and 10, of course, correspond to the number of cylinders in the engine.

A pair of upright guide rods 15 have their ends anchored in the top and bottom of the 65 housing 11 and extend through aligned bores in the ends of the bars 13 and 14. The fixed bar 13 is rigidly secured to the guide rods 15 by opposing clamping nuts 16, having screw threaded engagement with said rods. 70 The bar 14 is mounted on the rods 15, with freedom for vertical movement to carry the movable contacts 10 into and out of electrical engagement with the fixed contacts 9. To take the wear between the bar 14 on the 75 guide rods 15, I provide sleeve-like bushings 17 for said bar. These bushings 17 have sufficient length to keep the bar 14 against angular twisting movement on the guide rods 15 and in parallel relation to the bar 80 13. Coiled springs 18, encircling the guide rods 15, compressed between the lower ends of the bushing 17 and the bottom of the housing 11, are under strain to lift the bar 14 and thereby carry the movable contacts 85 10 into electrical engagement with the fixed contacts 9.

To depress the movable bar 14 and thereby carry the movable contacts 10 out of electrical engagement with the fixed contacts 9 90 to break the ignition circuit to the several spark plugs of the engine and, at the same time, lock said bar in such position, I provide a combination lock with a connection 95 from its tumbler actuated lock-bolt to said movable bar. The combination lock shown comprises a casing 19, tumblers 20, tumbler actuated lock-bolt 21, and dial equipped knob 22, having a stem 23 for operating the tumblers 20. The casing 19 is secured to the 100

top of the housing 11 and projects downward therein. The stem 23 extends through the housing 11 and dash 6, and the dial is mounted in a lined depression 24, formed in the face of said dash. By thus locating the dial-equipped knob 22, the same is within easy reach of the driver in starting and stopping his engine and simultaneously locking the same with the stopping thereof.

10 The lock-bolt 21 projects downward toward the movable bar 14 at one side thereof, and the connection between said lock-bolt and movable bar 14, heretofore referred to, is in the form of a stem 25. The upper 15 end of this stem 25 is rigidly secured to the lock-bolt 21 by screw threaded engagement. On the other or lower end of the stem 25 is a pair of arms 26, the free ends of which are arranged to project upwardly through apertures formed in the ends of the movable bar 14 and rigidly secured thereto by opposing clamping nuts 27. Obviously, by adjusting these nuts 27, the bar 14 may be horizontally set to cause the bushings 17 to freely slide 20 on the guide rods 15. Also by adjusting the nuts 16, the bar 13 may be horizontally positioned to cause a simultaneous engagement of the movable contacts 10 with the fixed contacts 9. To prevent an unauthorized 25 person from tampering with the wires 8, the same enter and leave the housing 11 through a branch conduit 28.

From the above description it is evident that a movement of the knob 22 to set the 30 lock-bolt 21 into a locking position will simultaneously break the ignition circuit and lock the movable contacts in inoperative positions. With the ignition system thus broken, it will be impossible for anyone to 35 start the engine without knowing the combination of the lock. A person knowing the combination, however, can very quickly manipulate the knob 22 to operate the tumblers, and thereby release the lock-bolt. As 40 soon as the lock-bolt is released, the springs 18 lift the bar 14, and thereby carry the movable contacts into electrical engagement with the fixed contacts to complete the ignition circuit. These springs 18 also perform 45 another important function, and that is, they constantly keep the movable contacts in electrical engagement with the fixed contacts

50

under the vibratory movement of the automobile.

What I claim is:

1. Switch mechanism including a casing, a pair of guide rods, a fixed bar, a movable bar mounted on the guide rods for movement toward and from the fixed bar, co-operating contacts carried by said two bars, springs operative on the ends of the movable bar to hold the contacts carried thereby in engagement with the contacts carried by the fixed bar, lock mechanism including a tumbler-actuated lock-bolt, and a connection between the lock bolt and movable bar for moving the said movable bar and the contacts carried thereby into circuit-open position.

2. Switch mechanism including a casing, a pair of guide rods, a fixed bar, a movable bar mounted on the guide rods for movement toward and from the fixed bar, co-operating contacts carried by said two bars, springs operative on the ends of the movable bar to hold the contacts carried thereby in engagement with the contacts carried by the fixed bar, means for angularly adjusting the fixed bar with respect to the movable bar, lock mechanism including a tumbler-actuated lock-bolt, and a connection between the lock bolt and movable bar for moving the said movable bar and the contacts carried thereby into circuit-open position.

3. Switch mechanism including a casing, a pair of guide rods, a fixed bar, a movable bar mounted on the guide rods for movement toward and from the fixed bar, co-operating contacts carried by said two bars, springs operative on the ends of the movable bar to hold the contacts carried thereby in engagement with the contacts carried by the fixed bar, lock mechanism including a tumbler-actuated lock-bar, and a connection extending from the lock-bolt to both ends of the movable bar for moving the said movable bar and the contacts carried thereby into circuit-open position.

In testimony whereof I affix my signature in presence of two witnesses.

OTTO FORTHMILLER.
